UNITED STATES PATENT OFFICE.

JOSEPH W. BISHOP, OF MUSKEGON, MICHIGAN, ASSIGNOR TO THE BRUNSWICK-BALKE-COLLENDER COMPANY, OF WILMINGTON, DELAWARE, A CORPORATION OF DELAWARE.

PIN-SETTING MACHINE.

Application filed June 29, 1925. Serial No. 40,280.

To all whom it may concern:

Be it known that I, JOSEPH W. BISHOP, a citizen of the United States, residing at Muskegon, in the county of Muskegon and State of Michigan, have invented certain new and useful Improvements in Pin-Setting Machines, of which the following is a specification.

This invention relates to a novel and improved pin setting machine of the hand operated type employed on bowling alleys. Machines of this type now in use are commonly provided with a handle for lowering them to position adjacent the alley bed, in which position the pins carried by the setter frame of the machine are deposited upon the bed, and then upon releasing the handle the setter frame is raised to its uppermost position by means of a counterweight connected to the frame. Other means such as springs, and pneumatic means controlled by valves, have been used also. It is the object of my invention to provide a pin setting machine of the hand operated type in which the raising of the setter frame is achieved without the use of such counterweights, springs or valves.

More specifically, the object of my invention is to provide a machine of the above type in which the lowering of the setter frame is done by hand as at present, but in which the raising of the frame is achieved by fluid pressure means and more particularly by hydraulic means.

Referring to the drawings in which I have shown a selected embodiment of my invention,

Fig. 1 is a rear elevation of a machine embodying my invention.

Fig. 2 is a section on the line 2—2 of Fig. 1.

Fig. 3 is a section on the line 3—3 of Fig. 1.

Fig. 4 is an elevation of the part of the machine shown in Fig. 3, but showing the setter frame in its lowered position.

Fig. 5 is a section on the lines 5—5 of Figs. 1 and 2.

Fig. 6 is a plan view of the machine and Fig. 7 is a diagram illustrating the operation of the machine.

Referring now to the drawings in detail I have shown at 1 an alley bed supporting at its sides posts 2 and braces 3 for the posts.

Supported on the posts are a pair of cross

bars 4 and 5 between which extend brackets 6, the above described structure forming a support for the machine.

Supported on the brackets are a plurality of guide tubes 7 within which reciprocate guide rods 8 secured to the setter frame 9. This setter frame may be of any desired form, but I have shown it herein as similar to the form described and claimed in my co-pending application Serial No. 16,332 filed March 18, 1925. The guide rods 8 are provided on one face thereof with teeth forming a rack 10 with which mesh pinions 11 mounted on a transverse shaft 12, this arrangement forming an equalizer to insure a uniform movement of the guide rods, as set forth in my aforesaid co-pending application.

The setter frame is adapted to be lowered by means of a handle 13 secured to arms 14 pivoted to ears 15 upon the support. Pivoted to the arms 14 are links 16 pivotally connected at their other ends to the setter frame. Operation of the handle from the position shown in Fig. 3 to that shown in Fig. 4 will obviously result in lowering the setter frame, this lowering movement being of sufficient extent to bring the frame in the proper position in relation to the alley bed 1, as shown in Fig. 4.

In order to raise the frame again to the position shown in Fig. 3 I provide on the support 6 a plurality of cylinders 17 within which reciprocate the pistons 18 mounted upon piston rods 19 secured to the setter frame. The cylinders 17 normally contain a suitable fluid, which for the purposes of illustration I have shown as water, although any other suitable fluid may be employed. This fluid is supplied from a pipe 20, through which the flow of the fluid is controlled by means of a suitable valve 21, the fluid passing through an accumulator 22, which is connected to the bottoms of the cylinders 17 by suitable pipes 23 and 24. The accumulator consists of a receptacle of comparatively large cross sectional area as compared to that of the cylinders and having a weight 25 slidably mounted thereon and snugly fitting the walls thereof. It will therefore be apparent that, as the setter frame is lowered, the fluid in the cylinders will flow through the pipes 23 and 24 back to the accumulator 22 and lift the weight 25, the pipe 20 being normally closed by the valve 21.

21. Then as the handle on the frame is released, the weight 25 will force the fluid back through the pipes 23 and 24 into the cylinders 17 and raise the pistons 18 and 5 consequently the frame 9. Connected to the tops of the cylinders 17 is a pipe 26 acting as a drain for any fluid which may leak by the pistons 18.

10 The operation of the device has been given during the description and it is not deemed necessary to repeat it here in detail. It will be apparent that downward movement of the setter frame to spot the pins is caused by actuation of the handle 13. When the 15 handle is lowered to the position shown in Fig. 4, the arms 14 and links 16 form a toggle which enables the operator to hold the frame down in its lowermost position with a minimum effort. The weight 25 is 20 lifted by the fluid during this downward movement, but as soon as the handle is released the weight descends in the receptacle in which it is mounted, thus causing the fluid to force the pistons upwardly and raise 25 the setter frame.

From the above it will be apparent that I have provided a pin setting machine of simple character and which will avoid the use of counterweights disposed in prominent positions, springs or valves. It will be noted that there are no valves between the cylinders and the accumulator and that none are necessary. The only valve provided is the valve 21 which is not normally used, its 30 only function being to replenish the supply of fluid.

40 I am aware that changes in the form, construction and arrangement of parts may be made without departing from the spirit and without sacrificing the advantages of the invention and I reserve the right to make all such changes as fairly fall within the scope of the following claims:

I claim:

45 1. A pin setting machine comprising a setter frame, means to lower said frame by hand, and fluid pressure means to raise said frame.

50 2. A pin setting machine comprising a setter frame, a handle connected to said frame to lower the same, and fluid pressure means to raise said frame and operating upon release of said handle.

3. A pin setting machine comprising a

setter frame, a handle to lower said frame, 55 a fluid acted on by the lowering of said frame, and reacting to lift said frame upon release of said handle.

4. A pin setting machine comprising a setter frame, a handle to lower said frame, 60 a fluid acted on by the lowering of said frame, an element moved by said fluid when acted upon by the lowering of said frame and reacting upon said fluid to raise said frame upon release of said handle.

5. A pin setting machine comprising a setter frame, a handle to lower said frame, 65 a cylinder containing fluid, a piston in said cylinder and moving against said fluid in one direction upon lowering of said frame, and means causing said fluid to move said piston in the opposite direction to raise said frame upon release of said handle.

6. A pin setting machine comprising a 70 support, a setter frame mounted for vertical movement on said support, a cylinder on said support and containing a fluid, an accumulator connected to said cylinder, a piston in said cylinder and connected to said frame, said fluid acting on said piston to hold said frame in raised position, and means to lower said frame.

7. A pin setting machine comprising a support, a setter frame mounted for vertical movement on said support, a cylinder on said support and containing a fluid, an accumulator connected to said cylinder by a pipe and comprising a receptacle having a weight vertically movable therein, a piston in said cylinder and connected to said frame, said fluid normally holding said frame in raised position by acting on said piston, and means to lower said frame, said lowering of said frame forcing the fluid in said cylinder into said accumulator and raising said weight, said weight reacting to cause said fluid to act on said piston and raise said frame upon release of said lowering means.

8. A pin setting machine comprising a 100 support, a setter frame mounted on said support for vertical movement, a handle having an arm pivoted to said support, a link pivoted to said arm and to said frame, said arm and said link straightening out to form a toggle as the frame is lowered by actuation of said handle.

JOSEPH W. BISHOP.
